(57) **CLAIM**

The ornamental design for an egg carton, as shown and described.

DESCRIPTION

FIG. 1 is a top, front, and right side perspective view of an egg carton according to our new design; FIG. 2 is a bottom, rear, and right side perspective view thereof;

FIG. 3 is a top, front, and right side perspective view thereof with upper lids in an open position;

FIG. 4 is a right side elevation view thereof;

FIG. 5 is a front elevation view thereof;

FIG. 6 is a top plan view thereof;

FIG. 7 is a rear elevation view thereof;

FIG. 8 is a left side elevation view thereof; and,

FIG. 9 is a bottom plan view thereof.
